UNITED STATES PATENT OFFICE

WILLIAM A. READY, OF BROOKLINE, MASSACHUSETTS

SPLIT D-HANDLE

Application filed February 19, 1929. Serial No. 341,132.

My invention aims to provide improvements in D-handles for shovels, forks and like, implements and particularly improvements in handles of the wooden split-D type.

5 In the drawings which illustrate a preferred embodiment of my invention:

Figure 1 is a part section and part elevation of a handle embodying the features of my invention;

10 Fig. 2 is an edge view of the handle shown in Fig. 1;

Fig. 3 is a section taken on the line 3—3 of Fig. 1; and

Fig. 4 is a section taken on the line 4—4 of

15 Fig. 1.

Referring to the embodiment of my invention selected for illustration in the accompanying drawings, I have shown a handle for shovels and like tools which is generally known as a split D-handle. The handle shown is made of wood with metal reinforcing elements, and comprises a wood stem 1 sawed through the middle lengthwise for a portion of its length and bent to provide two 25 diverging arms 2—2 between the ends of which is secured a grip-piece 3, as shown in Figure 1. The usual rivet 4 (shown in dotted lines, Fig. 1) is provided below the end of the saw cut 5 to prevent splitting of the 30 stem 1.

The grip-piece 3 is secured to the ends of the arms 2—2 by means of a tongue and slot connection which may be arranged in any suitable manner. One manner of arranging 35 the tongue and slot connection has been selected for purposes of illustration and will be described. Figures 1 and 3 show the free ends of the arms 2—2 divided by slots 6—6 which extend entirely through the arms 40 from their inner to their outer faces. The grip-piece is provided at each end with a tongue 7 which fits snugly into a cooperating slot 6 in an arm 2, thereby interlocking the grip-piece 3 with the arms to prevent relative 45 turning.

The grip-piece 3 is made of wood and has its grain lengthwise of the grip-piece for purposes hereinafter described. In this connection, the tongues 7—7 are made long enough 50 to extend through the slots 6—6 to the outer

edges of the arms 2—2, as clearly shown in Fig. 1.

In using a handle of the type illustrated there is a tendency to twist the grip-piece 3 and turn it relative to the side arms and, 55 therefore, with my interlocked construction this twisting stress is imparted to the portions 8 (Fig. 3) of the arms 2—2 at the sides of the slots 6—6. As the arms 2—2 are of wood there would be a tendency to split at the 60 ends of the slots 6—6. To prevent splitting of the arms, at their free ends, I have provided reinforcing elements 9 which are made of sheet metal and are fitted to the arms 65 as shown in Figs. 1 and 2.

Each reinforcing element is provided with a cap portion 9^a which fits over the exposed portion of the free end of an arm 2 and also extends over an adjacent portion of the grip-piece to conceal the tongue and slot joint and 70 back-support the portions 8. The cap fits closely to the arm and, therefore, the twisting stress will be transmitted to the reinforcing element which will prevent splitting of the arm 2. An extension 9^b from the cap 9^a extends down the side of an arm 2 and is preferably secured against the arm by a rivet 10, as 75 shown in Fig. 1.

When the elements of the handle are assembled, a rivet 10^a passes through holes 11 in 80 the reinforcing elements 9 and, through a bore 12 in the grip-piece 3 which passes through the axis thereof from one end of a tongue 7 to the other end of a tongue. This rivet 10^a is headed into countersunk portions 85 13 surrounding the holes 11 in the reinforcing elements thereby clamping the reinforcing elements in place and holding the arms against lateral spreading. The rivets 10 are put in last, so as to draw the tongues 7—7 90 down against the wood at the bottom of the slots 6—6.

The metal around the holes 11 in the reinforcing elements is strengthened by ribs 14 (Figs. 1, 2 and 4), shown as three in number 95 on each element, radiating from the holes 11 thereby to prevent distortion of the reinforcing elements when the rivet 10^a is headed to secure the parts together.

Heretofore, handles of the type illustrated 100

and described have been secured together in such a manner that the rivet passing through the grip-piece would hold all of the parts in fixed assembled relation so that a pull or push exerted on the grip-piece 3 would not pull it loose from the side arms 2-2. In my device, it should be noted that the rivet 10^a through the grip-piece 3 holds the reinforcing elements 9 against the side arms 2-2 and tongues 7-7 but does not prevent the grip-piece from being removed from the side arms by a pull exerted upon the grip. Such removal is prevented entirely by the attachment of the reinforcing element to the side arms by the rivets 10 at points remote from the rivet 10^a. Therefore, with my construction a downward thrust exerted upon the grip-piece 3 is distributed to the side arms 2-2 almost entirely through the contact of the tongues 7-7 at the bottoms of the slots 6-6, as shown in Fig. 1. An upward thrust is transmitted to the reinforcing elements 9 and through the reinforcing elements to the side arms 2-2.

Wood will shrink or swell depending upon atmospheric conditions and, therefore, there has been considerable trouble with wood split D-handles from this source. When the central rivet passes through the side arms and grip-piece, the side arms may shrink and the rivet become loose and project beyond the arms or reinforcing elements to such an extent that it may cause injury to the hands or clothing of a person handling the implement to which such a handle is attached. Besides this, the joint is somewhat loosened.

With my device, shrinkage of the side arms 2-2 does not affect the attachment between the reinforcing elements 9 and the grip-piece 3, because the reinforcing elements are clamped directly against the end grain of the tongues 7-7 and shrinkage of the wood does not, to any appreciable extent, affect the length of a piece of wood. Therefore, the rivet 10^a remains tight.

My handle construction is simple, inexpensive, and is exceedingly easy to assemble, besides being strong and durable and, therefore, is well adapted for relatively rough usage.

While I have illustrated and described a preferred embodiment of my invention, I do not wish to be limited thereby, as the scope of my invention is best defined by the following claims.

Claims.

1. A D-handle comprising, in combination, a one-piece stem having one end split to provide two diverging arms at one end of the stem, a grip-piece located between the free ends of said arms, tongue and groove means locking said grip-piece with said arms to prevent relative turning movement, the grooves extending entirely through the arms, a metal reinforcing element secured directly to each

arm, each of said reinforcing elements having a portion closely fitting the free end of an arm to conceal the tongue and groove means and strengthen the connection between the arm and grip-piece thereby to prevent splitting and means engaging only the grip-piece and the reinforcing elements to secure the reinforcing elements, arms and grip-piece together against lateral separation.

2. A D-handle comprising, in combination, a stem having one end split to provide two diverging arms, a grip-piece located between the free ends of said arms, tongue and groove means locking said grip-piece with said arms to prevent relative turning movement, a metal reinforcing element for each arm, each of said reinforcing elements having a portion closely fitting the free end of an arm to conceal the tongue and groove means and strengthen the connection between the arm and grip-piece thereby to prevent splitting and a rivet passing through the reinforcing elements, tongues and grip-piece and headed at its ends against the reinforcing elements to prevent lateral spreading of the arms, each reinforcing element having a portion extending part way down the side of an arm and a fastening element passing through the extended portion into the arm to hold it tightly against the arm and to provide the only fastening means engaged with the diverging arms.

3. A split D-handle comprising, in combination, a one-piece stem having one end split to provide diverging arms, said arms having slots extending entirely through and to their free ends, a grip-piece held between the diverging arms at their free ends and having tongues fitting into the cooperating slots in the diverging arms to prevent turning of the grip-piece relative to the said arms, a metal reinforcing element having a portion fitting over the free end of one of the said arms and preventing splitting adjacent to the slot in the arm, a second similar reinforcing element fitting over the free end of the other arm and means engaging only the grip-piece and the reinforcing elements to secure said reinforcing elements, arms and grip-piece together against lateral separation and other fastening means engaging only the arms and the reinforcing elements to secure the said reinforcing elements and the grip-piece in fixed relation to said arms.

4. A split D-handle comprising, in combination, a stem having one end split to provide diverging arms, said arms having slots through their free ends, a grip-piece held between the diverging arms at their free ends and having tongues fitting into the cooperating slots in the diverging arms to prevent turning of the grip-piece relative to the said arms, the slots extending entirely through the arms transversely and the tongues fitting into the slots and extending to the outer sur-

faces of the arms, a metal reinforcing element for each arm, each of said reinforcing elements having a portion fitting over the end of an arm to conceal the slot therein and reinforce the portions of the arm at the sides of the slot, each of said reinforcing elements contacting directly with the end of a tongue, a rivet passing through the reinforcing elements, tongues and grip-piece only and means securing said reinforcing elements to side arms independently of said rivet to prevent pulling the grip-piece and reinforcing elements free from the arms.

5. A split D-handle comprising, in combination, a wood stem divided at one end and formed into a pair of diverging arms, a wood grip-piece inserted between the free ends of said arms and having a tongue and slot connection at each end with a cooperating arm to prevent relative turning, the grain of the wood grip-piece being longitudinally thereof, a reinforcing element for each arm having a portion fitting over the tongue and slot connection and a rivet passing through the reinforcing elements and the grip-piece and holding said reinforcing elements in direct contact with the end grain of the grip-piece to prevent any loosening as and for the purposes described.

30 6. A split D-handle comprising, in combination, a wood stem divided at one end and formed into a pair of diverging arms, a wood grip-piece inserted between the free ends of said arms and having a tongue and slot connection at each end with a cooperating arm to prevent relative turning, the grain of the wood grip-piece being longitudinally thereof, a reinforcing element for each arm having a portion fitting over the tongue and slot connection and a rivet passing through the reinforcing elements and the grip-piece and holding said reinforcing elements in direct contact with the end grain of the grip-piece to prevent any loosening, as and for the purposes described, and said reinforcing elements having portions extending downwardly along the sides of the said arms and secured directly thereto to hold the parts in assembled relation.

50 7. In a split D-handle of the class described, a reinforcing element formed from metal and having a hole to permit passage of a rivet and a number of stiffening ribs radiating from the edge of said hole to prevent distortion of the metal around said hole when the rivet is headed to secure it in place.

In testimony whereof, I have signed my name to this specification.

WILLIAM A. READY.
